DISPLAY BOX

Filed March 14, 1928

3 Sheets-Sheet 1

The image contains two technical drawings of a rectangular box, labeled Fig. 1 and Fig. 2.

Fig. 1: This drawing shows a top-down perspective of a rectangular box. The top lid is hinged at the front and features a central rectangular cutout. The lid is labeled with numbers 3, 25, 4, 43, 42, 20, 13, 33, 28, 26, and 27. The main body of the box is labeled with numbers 13, 20, 26, 28, and 33.

Fig. 2: This drawing shows a side perspective of the box. The top lid is shown open, revealing a hinged internal panel labeled 43. The main body of the box is labeled with numbers 5, 42, 44, 45, 41, 35, 34, 23, 22, 24, 26, 28, and 33. The bottom of the box is labeled with numbers 24, 26, 28, and 33.

UNITED STATES PATENT OFFICE

JACOB MAYEROFF AND ALBERT J. QUINBY, OF BRONX, NEW YORK

DISPLAY BOX

Application filed March 14, 1928. Serial No. 261,668.

This invention relates to improvements in display boxes and particularly to foldable cardboard boxes.

The primary object of the invention resides in a display box which may be opened to display the contents thereof in a self supported inclined position whereby the goods may be attractively displayed upon the counters and in show windows of stores without the use of separate easels and the like.

Another object of the invention is to provide a display box which is constructed of a single blank of material which is scored and folded to include an easel which is foldable over the cover during shipment to reduce the size of the package, but which is capable of being swung beneath the bottom of the box for supporting the same in an inclined position.

A further object of the invention is the provision of a foldable display box which is simple in construction, easy to fold into box shape, inexpensive of manufacture, and strong and durable for the purposes intended.

With these and other objects in view, the invention resides in certain novel construction and combination and arrangement of parts, the essential features of which are hereinafter fully described, are particularly pointed out in the appended claim, and are illustrated in the accompanying drawing, in which:—

Figure 1 is a perspective view of our foldable display box in a closed position.

Figure 2 is a similar view but showing the box in a display position.

Figure 3 is a vertical longitudinal sectional view on the line 3—3 of Figure 1.

Figure 4 is a vertical transverse sectional view on the line 4—4 of Figure 1.

Figure 5 is a vertical longitudinal sectional view on the line 5—5 of Figure 2.

Figure 6 is a plan view of the blank before being folded into box forming position.

Referring to the drawings by reference characters, the letter A designates the blank from which our improved display box is formed, and which is preferably constructed of cardboard or other like bendable material. The blank is generally irregular in

plan and cut and scored by a suitable die to provide longitudinal fold lines 10, 11, 12, 13, 14 and 15. The fold line 13 extends the entire length of the blank. Transverse fold lines extend across the blank and are numbered 16, 17, 18, 19, 20 and 21 and serve with the longitudinal fold lines to provide a plurality of foldable flaps and areas which will now be identified.

The fold lines 13 and 14 bound the true bottom 22 of the box while a front wall 23 is contiguous to the bottom and is bound by the fold lines 18, 20 and 13. Co-extensive with the true bottom 22 is a back fold 24 bound by the fold lines 14 and 15 while a flap or easel 25 is co-extensive to the back fold 24 and is bound by the fold lines 15, 19 and 21. Co-extensive with the flap 25 are legs 26 and 27 foldable on the lines 15, 19 and 21 to provide spaced supporting legs for the easel. The legs 26 and 27 are cut at a bevel as at 28 so that when the bevelled edges are resting upon a supporting surface, the folded box will be supported in a forwardly tilted position as will be hereinafter explained. Interlocking back flaps 29 and 30 are co-extensive with the respective legs 26 and 27, the flap 29 being provided with a locking tongue 31 for reception in a slit 32 in the other back flap 30.

Bounding the ends of the front 23 are side walls 33 and 34 while disposed to one side of the side walls are flaps 35 adapted to fold inwardly when the box is in a set-up position. Foldable beneath the true bottom 22 when in a set-up position are bottom locking flaps 36 and 37 which are contiguous to the side walls 33 and 34 respectively, the flap 37 being provided with locking tongues 38 for reception through slits 39 in the flap 36.

Bounded by the fold lines 16, 17, 12 and 13 is a back wall 40 to one side of which extends an inner bottom flap 41 while a cover or lid 42 extends upon the opposite side. The cover is scored midway between its ends as at 43 for holding the same upon itself when in an open display position while a tab 44 is cut from the cover and projects thereabove when in display position as shown in Figures 2 and 5 of the drawings. Suitable advertising indicia may be printed upon the tab 44.

The cover 42 is bound by the lines 12 and 10, and co-extensive therewith is a front locking flap 44 which fits down within the box against the front wall 23 when the cover is in a closed position, and which fits flat against the back wall 40 when the lid is held in an open display position. The ends of the flaps 35 serve to retain the cover in an open position.

In setting up the box, the blank is folded on the lines indicated so that the securing flap 45 which extends from the back wall 40 may be adhesively connected to the inner face of the side wall 34. This brings the back wall 40 opposite the front wall 23 and the sidewalls 33 and 34 opposite to each other. The flap 41 is folded to lie flat against the bottom 22 on the inside thereof to reinforce the bottom adjacent the rear wall, while the locking flaps 36 and 37 are folded under the bottom wall and the tongues 38 inserted through the slits 39 for interlocking engagement. The cover 42 is normally folded down over the open side of the box after the contents have been packed therein with the cover flap 44 extending downward against the front wall 23. With the cover in a closed position, the easel 25 is swung or folded over the cover with the back fold 24 flat against the back wall 40 of the box and with the interlocking flaps 29 and 30 interposed therebetween, while the legs 26 embrace the opposite sides of the box as clearly shown in Figures 1, 3 and 4 of the drawings. The easel 25 may be temporarily held against movement by sealing the same to the box. When it is desired to open the box to display the contents thereof, the easel is swung back beneath the bottom of the box with the folds 24 and 25 flat against the bottom and the legs 26 and 27 depending therefrom. The bevelled edges 28 of the legs rest upon the supporting surface to support the box in a forwardly tilted position with the interlocking flaps 29 and 30 bridging the same. It will be noted that when the easel is swung to a supporting position, it is disposed approximately midway between the front and back of the box and provides a rigid support therefor. The cover is next lifted and folded upon itself on the fold line 11 and the flap 44 inserted and held against the rear wall by the inwardly extending flaps 35. The display tab 43 projects above the fold in the cover and may contain suitable advertising indicia. When the box is in a closed position, the easel 24 overlies the display tab to prevent accidental breakage of the same, while the inner bottom flap 41 acts as a reinforcement for the bottom when the box is in a display position.

While we have described what we deem to be the most desirable embodiment of our invention, it is obvious that many of the details may be varied without in any way de-

parting from the spirit of our invention, and we therefore do not limit ourselves to the exact details of construction herein set forth nor to anything less than the whole of our invention limited only by the appended claim.

What is claimed as new is:—

A display box constructed of a single blank of material comprising a continuous bottom, a front wall foldable at right angle to said bottom, side walls foldable at right angle to said front wall, interlocking bottom reinforcing flaps contiguous with said side walls and foldable with respect thereto to underlie said bottom, a rear wall contiguous with respect to one of said side walls, a cover swingable on one of the sides of said rear wall, an easel embodying a portion co-extensive with said bottom, side leg flaps extending from the ends of said portion and having beveled supporting edges, and interlocking flaps co-extensive with said leg flaps and foldable relative thereto.

In testimony whereof we have affixed our signatures.

JACOB MAYEROFF.
ALBERT J. QUINBY.
